UNITED STATES PATENT OFFICE.

JOSEPH R. BAYER, OF NEW YORK, N. Y.

PIN-TICKET.

1,383,063.

Specification of Letters Patent. Patented June 28, 1921.

Application filed June 25, 1920. Serial No. 391,572.

To all whom it may concern:

Be it known that I, JOSEPH R. BAYER, a citizen of the United States, and a resident of the city of New York, borough of Manhattan, in the county of New York, and State of New York, have invented a new and Improved Pin-Ticket, of which the following is a full, clear, and exact description.

10 This invention relates to improvements in pin tickets, and more particularly to an improved construction of metal fastener forming a part of the pin ticket and facilitating the engagement of the pin ticket with the 15 goods or article on which it is to be secured.

A further object is to provide a pin ticket folding fastener which is composed of a single piece of wire and which may be operated to puncture the goods and secure the ticket in place or may be positioned over the edge of the goods or over the edge of a cloth or other article so as to hold the pin ticket firmly in place without scratching or 25 marring the cloth or other article.

A further object is to provide improvements of the character stated which can be manufactured and sold at an extremely low price, which can be quickly and easily manipulated either to secure the pin ticket or 30 permit the removal thereof and which will in every respect efficiently perform the functions for which it is intended.

With these and other objects in view the 35 invention consists in certain novel features of construction, and combinations and arrangements of parts, as will be more fully hereinafter described and pointed out in the claim.

40 In the accompanying drawings—

Figure 1 is a rear perspective view illustrating my improved pin ticket.

Fig. 2 is a view in elevation or plan illustrating my improved pin ticket in position 45 in a piece of cloth or other goods.

Fig. 3 is a view in longitudinal section on the line 3—3 of Fig. 2, showing in dotted lines the initial position of the pin ticket.

Figs. 4 and 5 are views in longitudinal 50 section illustrating the operation of the device when positioned over the edge of the piece of cloth or other article.

Fig. 6 is a fragmentary perspective view 55 illustrating my improved device in position on a glove or similar article.

Fig. 7 is a view in section on the line 7—7

of Fig. 6, showing the initial position of the pin ticket.

Fig. 8 is a similar view showing the final securing position of the pin ticket. 60

Fig. 9 is an exaggerated end view of the prong 4.

Fig. 10 is an exaggerated perspective view of the end of the prong.

A represents a pin ticket which comprises 65 a piece of cardboard or other suitable material of any desired shape and B represents my improved metal fastener secured to and forming a part of the pin ticket.

My improved metal fastener comprises a 70 single piece of wire which is slightly elastic and which is preferably rectangular in cross-section, although, of course, the invention is not limited to the precise cross-sectional shape of the wire. 75

Both ends of the wire are projected through the pin ticket A as shown at 1, leaving an intermediate portion of the wire 2 on the outer face of the ticket, and this puncturing of the ticket by the wire is preferably at the upper portion of the ticket as clearly shown in Fig. 2. One end of the wire, which constitutes the lower portion thereof in normal use, is bent upwardly and flat against the inner face of the pin ticket 85 A as shown at 3, and is then bent at a sharp right angle forming a relatively short sharp prong or spur 4.

The other end of the wire, which constitutes the normal upper portion thereof, extends upwardly flat against the inner face of the ticket A as shown at 5, is then bent outwardly and then downwardly as shown at 6, and projects downwardly an appreciable distance past the prong or spur 4 and constitutes a tongue 7 having a sharp free end 8. 90

The outer end of the spur 4 is made with a sharp end 9 of general pyramidal shape providing a beveled surface 10 which facilitates the positioning of the fastener in the goods or on the article as will more fully hereinafter appear. 100

It is to be understood that the tongue 7 is normally against the sharp outer end of the 105 spur or prong 4 and that the elasticity of the metal is employed to hold the fastener in its securing position.

When my improved pin ticket is used in connection with cloth or other goods as indicated by the reference numeral 11, the operation is ordinarily as follows: The free or 110

lower end of the pin ticket A is grasped between the thumb and finger of the user and the sharp end 8 of tongue 7 is directed through the material by exerting a longitudinal pull on the pin ticket. This movement of the tongue through the material 11 is limited by the bend 6 in the wire and when the ticket is released, the elasticity of the metal of the fastener will move the tongue 7 and the spur or prong 4 toward each other so that the spur or prong either punctures the material or embeds itself therein sufficiently to hold the pin ticket in place. To remove the pin ticket, it is simply necessary to force the ticket A and the free end of the tongue 7 slightly apart when the fastener is engaged in the cloth.

In Figs. 3 and 4 I illustrate the operation of the device when slipped over the edge of a piece of goods or other article, and in this operation the edge of the goods by reason of its engagement with the inclined or cam face 10 of the prong or spur 4, exerts a cam action to force the tongue 7 outwardly until the pin ticket is in operative position when the tongue will swing inwardly and the material will be effectually engaged.

In positioning my improved ticket over the edge of a glove 12 as indicated in Figs. 6, 7 and 8, I preferably manually force the tongue 7 outwardly a distance sufficient to accommodate the glove and then either force the tongue back until it is normally positioned or allow it to spring into position so as to secure the bite or engagement of the spur with the glove.

While in the drawings I have illustrated a prong or spur as passing through the goods or article, it is obvious that in many cases the spur will only embed itself or indent the

goods and will securely hold and the reason for manually operating the tongue in placing the same over a glove or other similar article is to prevent scratching or injuring the article by the fastener. 45

It will thus be noted that I provide a pin ticket having a metal fastener which is provided with a sharp spur or prong projecting at right angles from the ticket and also provide a sharp tongue extending substantially 50 parallel to the ticket and across the sharp outer end of the spur. While I have illustrated several ordinary uses of this pin ticket, it is obvious that the invention is not limited to the particular use, but broadly to 55 the article itself.

Various slight changes might be made in the general form and arrangement of the parts described without departing from the invention, and hence I do not limit myself 60 to the precise details set forth, but consider myself at liberty to make such changes and alterations as fairly fall within the spirit and scope of the appended claim. 65

I claim:

A pin ticket, comprising a card, a fastener secured to the card and comprising a single piece of wire having both ends of the wire projected through the card and bent in the same direction and located substantially 70 in alinement and against the rear face of the card, one extreme end of the wire bent at a substantial right angle to the card and forming a spur having a sharp outer end, and the other end of said wire bent forming 75 a tongue located normally parallel to the card and extending across the outer end of the spur.

JOSEPH R. BAYER.
